(57) **CLAIM**

The ornamental design for a display screen or portion thereof with animated graphical user interface, as shown and described.

DESCRIPTION

FIG. 1 is a front view of a display screen or portion thereof with animated graphical user interface, showing my new design;

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the transitional image sequentially transitions between the images shown in FIGS. 1-5. The process or period that one image transitions to another image; forms no part of the claimed design.

In the drawings the dot-dash broken lines show is a portion of the display panel that forms no part of the claimed design. The dashed broken lines showing the outlined text is provided for the purpose of illustrating portions of the animated graphical user interface that forms no part of the claimed design.
